(57) **CLAIM**

The ornamental design for a bottle holder, as shown and described.

DESCRIPTION

FIG. 1 is a perspective front view of an embodiment of my bottle holder;

FIG. 2 is a front view of an embodiment of my bottle holder;
FIG. 3 is a rear view of an embodiment of my bottle holder;
FIG. 4 is a left side view thereof; the right side is the same;
and,

FIG. 5 is a top view thereof.

The banding lines in the middle of the Figures indicate creases or folds in the material.
